UNITED STATES PATENT OFFICE.

GEORGE ALFRED BOUVIER, OF OAK PARK, ILLINOIS, ASSIGNOR TO WESTERN ELECTRIC COMPANY, INCORPORATED, OF NEW YORK, N. Y., A CORPORATION OF NEW YORK.

STRAND-TWISTING APPARATUS.

Application filed January 27, 1926, Serial No. 84,000. Renewed May 10, 1928.

This invention relates to strand twisting apparatus, and its primary object is the provision of an improved apparatus requiring a minimum of operating power for efficiently and uniformly twisting one or more strands at a high rate of speed.

Improved apparatus embodying the present invention is particularly well adapted for use in a strand twisted apparatus of the type fully illustrated and described in the copending application of G. A. Bouvier, Serial No. 80,709, filed Jan. 12, 1926, which apparatus produces a flexible electrical conductor by twisting a plurality of tinsel served threads around a cotton core.

In accordance with one embodiment of the present invention, a cotton core and a plurality of tinsel served threads are drawn through a twisting mechanism by a capstan which advances the twisted strand through a tubular flier arm, which arm carries the strand around an axis of rotation coinciding with the rotating axis of the twisting mechanism. The flier arm is of stream-line construction, being tapered in a direction opposite to that of its rotation, thereby decreasing the amount of power required for operating the apparatus. Bushings associated with the flier are rotated around the twisted strand in the direction of the twist and frictionally engage the twisted strand to prevent untwisting thereof while passing through the flier arm, thereby maintaining the twists uniform throughout the entire length of the strand.

Other objects and features of the invention will become apparent in the following detailed description, reference being had to the accompanying drawings, wherein

Fig. 1 is a plan view of an apparatus embodying the invention;

Fig. 2 is a side elevation thereof;

Fig. 3 is an enlarged fragmentary plan section taken on the line 3-3 of Fig. 2;

Fig. 4 is an enlarged fragmentary section taken on the line 4-4 of Fig. 1;

Fig. 5 is an enlarged fragmentary section taken on the line 5-5 of Fig. 3;

Fig. 6 is an enlarged fragmentary detail view showing the take-up capstan and the associated take-up mechanism;

Fig. 7 is an enlarged fragmentary section taken on the line 7-7 of Fig. 4;

Fig. 8 is a fragmentary section taken on the line 8-8 of Fig. 7;

Fig. 9 is an enlarged detail section taken on the line 9-9 of Fig. 2, and

Fig. 10 illustrates diagrammatically the manner in which the improved apparatus applies tinsel covered thread to a cotton core.

Referring now to the drawings in detail, and particularly to Figs. 1 and 2 thereof, the improved apparatus is mounted in and upon a frame which comprises a base plate member 20, a vertical wall 21 and a top plate member 22. Rotatably journaled in suitable bearings formed in the frame members 20 and 22 is a vertically disposed shaft 23 (Fig. 3), which is driven by an electric motor 24 (Fig. 2) by means of suitable gearing indicated at 25. A gear 26 (Figs. 1 and 4) is secured to the shaft 23 and meshes with a gear 27 keyed to a collar 28, which collar forms part of the driving element of a clutch 29 (Fig. 2) through which the shaft 23 may be operatively connected to and disconnected from a vertically disposed shaft 30, as disclosed in the aforementioned copending application.

Secured at opposite ends of the shaft 30 are gears 32 and 33 which mesh with gears 34 and 35, respectively, the gears 34 and 35 being meshed with gears 36 and 37, respectively, (Figs. 3, 4 and 5). The gears 36 and 37 are keyed to vertically disposed trunnions 38 and 39, respectively, which are disposed in axial alignment and which carry heads 41 and 42, respectively, of a flier 43. The flier heads 41 and 42 are interconnected by a pair of tubular arms 44 and 45 as clearly illustrated in Fig. 2, the flier arms 44 and 45 are of stream-line construction, the advancing portions thereof presenting a curved or blunt surface which tapers rearwardly, terminating in a trailing edge. This construction of the flier arms materially decreases the amount of power required for operating the apparatus since it decreases air resistance by preventing vacuum pockets from being formed behind the trailing portions of the arms.

Disposed intermediate the flier heads 41 and 42 is a yoke 46 which is held stationary during the rotation of the flier by means of suitable planetary gearing (not shown). For a detailed illustration and description of a planetary gearing construction which is particularly suitable for use with the present embodiment of the invention, refer-

ence is made to the above mentioned copending application. The details of this construction have been omitted from the present application for the sake of simplicity 5 since a full disclosure thereof is not essential to a complete understanding of the present invention.

Rotatably journaled upon a tubular portion 48 (Fig. 4) of the frame member 22 is 10 a spider-like member 49 having a plurality of arms 50 (Fig. 1). Rotatably journaled in the outer end of each arm 50 is a spindle 52 carrying a removable supply reel. As shown in the drawings (Fig. 1), seven supply 15 reels are provided, six of the supply reels being adapted to hold tinsel served threads, and one of the supply reels being adapted to hold a supply of cotton core. The supply reel which holds the cotton core is identical 20 in construction with the several supply reels which hold the tinsel served threads, but for the purpose of this explanation it is identified by the reference character 53, the other supply reels being identified 25 by the reference character 54. Aligned with the cotton supplying reel 53 is a sheave 55 mounted on a bracket 56 carried by the member 49. Associated with each of the supply reels is a strand tensioning device, each of 30 which comprises a guide sheave 58 mounted on the free end of a lever 59 which is pivotally carried by the spider arm 50 with which the particular sheave is associated. For a more detailed disclosure and description of 35 the supply reel mountings and the strand tensioning device, reference is made to the above mentioned copending application.

Seated in the upper end of the tubular portion 48 is a plate 60 having an aperture 40 61, the axis of which is coincident with the axis of the trunnion 38 (Figs. 1 and 4). The plate 60 is also provided with six apertures 62 which are equi-distantly spaced from the aperture 61 and from each other. 45 In the operation of the apparatus, the cotton core is passed through the aperture 61 and the tinsel served threads are passed through the aperture 62.

Keyed to the trunnion 38 is a gear 64 50 meshing with a gear 65 rotatably journaled on a shaft 66 which is rigidly secured within the frame (Fig. 4). Constrained to rotate with the gear 65 is a gear 68 meshing with a gear 69 which is formed integrally with 55 a tubular member 70 rotatably mounted upon a tubular extension 71 of the trunnion 38. The ratio between the gears 69 and 68 is such that the tubular member 70 makes two revolutions for each revolution of the flier 60 43. Rotatably journaled upon the tubular member 70 is a sleeve 73 having a capstan 74 formed integrally therewith. A gear 75 formed integrally with the sleeve 73 meshes with a gear 76 which is constrained to rotate 65 with the gear 68, the gears 75 and 76 being

so proportioned that the capstan 74 rotates at a speed which is less than that of the tubular member 70 but greater than that of the filter 43. The purpose of this construction will presently appear.

Rigidly secured within the tubular member 70 and disposed concentrically therewith is a tube 78, one end of which projects downwardly into a bore 79 formed in the trunnion 38 (Fig. 4). Seated upon the upper end of the tubular member 70 and rigidly secured thereto is a cap or twisting member 80 which carries sheaves 81, 82, 83 and 84 aligned with grooved rollers 85, 86, 87 and 88, respectively, the grooved rollers 85, 86, 80 87 and 88 being angularly disposed with respect to the capstan 74 and being carried by the member 80. The grooved rollers 85 and 87 are aligned with the upper portion of the capstan 74 and are adapted to deliver the 85 twisted strand thereto, whereas the grooved rollers 86 and 88 are aligned with the lower portion of the capstan 74 and are adapted to receive the twisted strand as it leaves the capstan. Although four sheaves and four 90 grooved rollers are shown (Fig. 7), functional use is made of only two of the sheaves and two of the grooved rollers, as for instance the sheaves 81 and 82 and the grooved rollers 85 and 86, the sheaves 83 and 84 95 and the grooved rollers 87 and 88 being provided to dynamically balance the member 80.

Connected to the lower end of the tube 78 and disposed in axial alignment therewith is 100 a tubular member 90 which is constrained to rotate with the tube 78 by means of a bushing 92 having one end secured to the lower end of the tube 78 and its opposite end threaded on the upper end of the tubular member 90. Formed on the lower end of the tubular member 90 is a bevel gear 94 which meshes with a bevel gear 95 formed at one end of a bell mouth bushing 96 rotatably journaled in the head 41. The 105 bushing 96 is so disposed within the head 41 that it interconnects the flier arm 44 and the tubular member 90, thereby providing a continuous passage for the twisted strand between the tube 78 and the flier arm 44.

Mounted within the trunnion 39 and disposed in axial alignment therewith is a tubular member 98 having a plate 99 rigidly secured at its upper end (Fig. 5), the plate 99 being fastened to the yoke 46 thereby 110 serving to hold the member 98 stationary during the operation of the apparatus. Formed on the lower end of the tubular member 90 is a bevel gear 100 meshing with a bevel gear 101 formed at one end of a horizontally disposed bushing 102 rotatably 115 journaled in the head 42. The bushing 102 and the tubular member 98 are provided with cooperating bell shaped mouths or 120 openings and are positioned so as to form 125

a smooth continuous passage for the twisted strand.

Positioned above the tubular member 98 and carried by the yoke 46 is a capstan 104 having a plurality of peripheral grooves (Fig. 5), the inner one of which is in alignment with the axis of the tubular member 98. Associated with the capstan 104 is an idler roller 105 (Fig. 6) having a plurality of peripheral grooves cooperating with the peripheral grooves of the capstan to receive the twisted strand as it is withdrawn from the tubular member 98. Disposed above the capstan 104 and carried by the yoke 46 is a strand distributing device 106 which is employed to distribute the twisted strand upon a take-up reel 107 removably mounted upon the yoke 46. Suitable gearing (not shown) is provided for driving the capstan 104 at a surface speed which is less than the surface speed of the capstan 74. The purpose of this construction will become apparent from the following description of the operation of the apparatus.

In the operation of the above described apparatus, a supply reel 53 holding a supply of cotton core and six supply reels 54 holding tinsel served threads are placed upon the spindles 52, the supply reel 53 being placed upon that spindle 52 which is aligned with the sheave 55. The cotton core is passed over the sheave 58 aligned therewith, over the sheave 55, and through the aperture 61 in the plate 60. The tinsel served threads are passed over the sheaves 58 aligned therewith and through the apertures 62 in the plate 60. As diagrammatically shown in Fig. 10, the cotton core and the tinsel served threads are then guided by the sheave 81 to the grooved roller 85 which delivers them to the capstan 74. After one or two turns of the cotton core and the tinsel served threads have been wrapped around the capstan 74, they are threaded around the grooved roller 86 which guides them to the sheave 82 from which they are passed downwardly through the tube 78, the tubular member 90, the rotating bushing 96, the flier arm 44, the rotating bushing 98, and then upwardly through the tubular member 102 to the capstan 104. After several turns of the cotton core have been wrapped around the capstan 104 and the associated grooved roller 105, they are guided to the take-up reel 107 by the distributing mechanism 106. The motor 24 is then connected to any suitable source (not shown) of electrical energy, thereby continuously driving the shaft 23. The shaft 30 is operatively connected to the shaft 23 by means of suitable mechanism (not shown) which may be similar to that described in the above mentioned copending application.

Rotation of the shaft 30 is transmitted

through the gears 32 to 37 inclusive to rotate the flier 43 in a clockwise direction, the gears 32, 34 and 36 serving to drive the upper head of the flier, and the gears 33, 35 and 37 serving to drive the lower head thereof. Rotation of the flier 43 is transmitted to the tubular member 70, the tube 78, and the twisting member 80 through the gears 64, 65, 68 and 69 (Fig. 4). As hereinbefore described, the ratio between these gears is such that the tubular member 70 together with the twisting member 80 makes two complete revolutions for each revolution of the flier 43. Furthermore, the construction is such that the direction of rotation of the twisting member 80 is the same as that of the flier 43. It is obvious therefore that the twisting member 80 will form two complete twists in the cotton core and the tinsel served threads for each revolution of the flier 43.

The capstan 74 is driven from the trunnion 38 through the gears 64, 65, 76 and 75. As hereinbefore described, the ratio between these gears is such that the capstan 74 travels at a speed which is slightly greater than the speed of the flier 43 and slightly less than the speed of the twisting member 80. It is obvious therefore that each revolution of the flier will cause a portion of the twisted strand to be applied on the upper portion of the capstan 74 by the grooved roller 85 while another portion of the strand is advanced by the capstan 74 to the grooved roller 86 from which it is drawn by the lower capstan 104, over the pulley 82, through the tube 78, through the tubular member 90, etc., as hereinbefore described.

During the operation of the apparatus, it will be noted that the tubular member 90 and the bushings 96 and 102 are rotated in the direction of the twists in the twisted strand and the inner walls thereof frictionally engage the moving strand, thereby preventing untwisting thereof as it is drawn from the twisting apparatus to the take-up spool. This insures that the twists in the finished product will be uniform and will remain substantially as originally formed by the twisting member 80. Furthermore, due to the capstan 104 being driven at a slightly lower surface speed than the capstan 74, it is apparent that the capstan 74 will tend to advance the strand to the roller 86 slightly faster than it is withdrawn therefrom by the capstan 104. This arrangement, obviously, tends to introduce a certain amount of slack in the strand between the capstans 74 and 104. However, since only one or two turns of the strand are wrapped around the capstan 74, the strand is permitted to slip around this capstan as the tension thereon decreases, thereby serving to maintain the tension on the strand between the two capstans substantially constant. The double

- capstan arrangement also decreases the amount of tension on the strand as it is advanced through the apparatus since it eliminates binding to a certain extent, thereby decreasing the frictional resistance presented to the moving strand.
- It has been found in actual practice that a minimum amount of power is required for operating a twisting apparatus having a flier constructed in accordance with the features of this invention; wherein the flier arms are stream-lined as shown in the drawings. This construction of the flier arms substantially decreases the operating cost of the apparatus which, obviously, decreases the cost of the finished product.
- Although the invention as herein illustrated and described is particularly well adapted for use in connection with an apparatus for twisting a plurality of strands around a central core, it should be understood that the invention is capable of other applications and should be limited only by the scope of the appended claims.
- What is claimed is:
1. In strand twisting apparatus, strand twisting means, strand take-up means, a tubular member for carrying the twisted strand bodily around an axis of rotation and for guiding the strand from the twisting means to the take-up means, means for advancing the strand through the tubular member, and means for rotating the tubular member and said advancing means around a common axis of rotation other than that of the take-up means.
  2. In strand twisting apparatus, strand twisting means, means for advancing the strand therethrough, a rotatable member tapered in a direction opposite to that of its rotation for guiding the strand from the strand twisting means, means for rotating said member to rotate a portion of the strand bodily around an axis of rotation, and a plurality of positively rotated bushings engaging the strand to prevent untwisting thereof as it is advanced through the apparatus.
  3. In strand twisting apparatus, strand twisting means, means for rotating a portion of the strand bodily around an axis of rotation, the latter means comprising a rotating member having a blunt advancing
- portion and a tapered trailing portion, a rotatable bushing for guiding the strand, and means for positively rotating the bushing around the strand.
4. In strand twisting apparatus, strand twisting means, strand take-up means, a bushing interposed therebetween for carrying the twisted strand bodily around an axis of rotation, and for guiding the twisted strand to said take-up means, and means for positively rotating said bushing around the twisted strand in the direction of the twists to prevent untwisting of the strand as it is delivered to the take-up means.
5. In strand twisting apparatus, strand twisting means, strand take-up means, a tubular member for rotating the twisted strand bodily around an axis of rotation other than that of the take-up means, a capstan for delivering the twisted strand to said tubular member, and means for rotating the capstan and the twisting means around a common axis of rotation.
6. In strand twisting apparatus, strand twisting means, strand take-up means, a flier interposed therebetween for rotating the twisted strand bodily around an axis of rotation, said flier comprising a tubular member having a rotatable bushing positioned at one end thereof, and means for positively rotating said bushing around the twisted strand in the direction of the twists to prevent untwisting of the strand as it is delivered to the take-up means.
7. In strand twisting apparatus, strand twisting means, strand take-up means and a flier interposed therebetween for rotating the twisted strand bodily around an axis of rotation, said flier including a tubular member through which the strand is advanced and means associated therewith for preventing untwisting of the strand, the said tubular member having a blunt advancing portion and a tapered trailing portion and being shaped so as to guide the strand through a path conforming to the curve which a strand assumes when its ends are fixed to spaced points on an axis of rotation and it is rotated bodily around the axis.

In witness whereof, I hereunto subscribe my name this 12th day of January A. D. 1926.

GEORGE ALFRED BOUVIER.
